UNITED STATES PATENT OFFICE.

WILLIAM A. COURTLAND, OF BROOKLYN, NEW YORK, ASSIGNOR TO AMERICAN PIN COMPANY, OF WATERBURY, CONNECTICUT, A CORPORATION OF CONNECTICUT.

ARTICLE-FEEDING MEANS.

1,230,870.

Specification of Letters Patent. Patented June 26, 1917.

Application filed September 4, 1915. Serial No. 49,064.

To all whom it may concern:

Be it known that I, WILLIAM A. COURTLAND, a citizen of the United States, residing in the borough of Brooklyn, county 5 of Kings, and State of New York, have invented certain new and useful Improvements in Article-Feeding Means, of which the following is a specification.

This invention relates more especially to 10 safety pin machines, and has for its primary object to provide an improved construction, combination and arrangement of parts in a machine of this character for feeding caps and the like in a predetermined order. One 15 of the objects of the present invention is to provide an article holder of improved construction embodying a plurality of chambers or receptacles. Another object is to provide improved means for moving said 20 article holder to bring said chambers or receptacles successively into register with a chute which delivers them to mechanism for applying them separately to safety pin blanks such for example, as that shown and 25 described in my copending application, Serial Number 30,762, filed on May 27th, 1915. Other and further objects will appear in the specification and be pointed out in the appended claims, reference being had 30 to the accompanying drawings in which my invention is adapted to a safety pin machine.

In the drawings,—

Figure 1 is a plan view of portions of a safety pin machine embodying my improve- 35 ments;

Fig. 2 is a section on the line II—II, Fig. 1;

Fig. 3 is a section on the line III—III, Fig. 1;

Fig. 4 is a plan view of the lower end of 40 the shield-feeding chute;

Fig. 5 is a section on the line V—V, Fig. 4;

Fig. 6 is an enlarged vertical section of 45 the shield container;

Fig. 7 is a bottom plan view of the same;

Fig. 8 is a fragmentary top plan view of the container supporting plate;

Fig. 9 is an enlarged fragmentary view 50 of the container;

Fig. 10 shows in detail one of the latches used for holding the container in desired positions.

Fig. 11 is a side elevation of the lower

end of the chute and shield-feeding mech- 55 anism, parts being broken away and parts shown in section.

Referring first to Fig. 1 of the drawings, my copending application, Serial Number 30,762, refers to a cam shaft 13 which derives its power from a main drive shaft 14 by means of bevel gears 15. Said shaft 14 has keyed thereto a worm gear 16 which operates suitable mechanism for conveying safety pins from the necking apparatus 60 which is shown and described in said application. Prior to its delivery to this conveyer however, the necked blank is delivered to the capping mechanism which, as shown and described in the above mentioned application, includes the following parts.

Referring to Fig. 3, a bracket 65 is mounted upon a portion of the frame and has secured thereto one end of a spring 66, the other end of said spring being connected to 75 a pin 67 on a slide 68, which is reciprocated by a cam 70. Said cam is keyed to the cam shaft 14 and comprises inner, intermediate and outer runs. The slide 68 is provided with a cap holding recess at its inner end, 80 into which the caps are separately discharged at certain times during the operation of a cam-operated slide 68 as shown and described more fully in my above identified copending application. Adjacent the 85 lower end of the section 64 of the chute, a leaf spring 72 carries a spur 74 (see Fig. 4) which projects through the side wall of the chute. The inner end of said spur is beveled and projects from the inner wall suffi- 90 ciently to yieldably retain the caps in the chute. Said section 64 of the chute carries a laterally projecting guide 75 within which reciprocates a slide 76, said slide being suitably connected to the upper arm 77 (see Fig. 95 3) of a lever which is journaled on a shaft 78 and provided with a cam arm 79 carrying a cam roller 80 operated by a cam 81. Roller 80 is pressed to the cam 81 by yield- 100 able means, not shown on the drawings. A feed finger 84 (see Fig. 4) which is pivotally connected to the lower end of slide 76 is pressed by a spring 85 and carries at 105 its lower end a spur 86 which is adapted to engage the lowest cap in the chute and force it over the yieldable spur 74. A transverse pin 87 projects on opposite sides of the lower end of feed finger 84. Near

the end of the downward movement of slide 76, the pin 87 on one side rides over a wedge-shaped barrier 88 and elevates the spur 86 sufficiently to release the cap into recess 71 in slide 68. On the return stroke of said feed finger, the oppositely projecting end of pin 87 rides over a strip 89 until it reaches a recess 90, into which it drops to bring the spur 86 into engagement with the next lower cap or shield. As shown in Fig. 3, section 64 of the chute is connected by a turn 91 with an upper section 92 of the chute which leads from a base plate 93 which is mounted on a bracket 94 above the safety pin machine. A reinforcement 95 is arranged between the bracket 94 and chute section 92. Bracket 94 is provided with a boss 96 and a lower bracket arm 97 within which is journaled a vertical shaft 98 to which is keyed a ratchet 99. As shown best in Figs. 1 and 3, ratchet 99 is periodically operated by a pawl 100 journaled on a pin 101 carried by a radial arm 102 which is journaled freely on the shaft 98. A rod 103 which is reciprocably mounted in a guide 104 is connected to the pin 101 and serves to drive the pawl 100. As shown in Fig. 1, the guide 104 is T-shaped, a collar 105 being mounted on the rod 103 to prevent the rod from entering too far into the guide under the action of a spring 105' (Fig. 2). A reciprocatory rod 106 which is spaced from the rod 103, but in alinement therewith, is connected at 107 (see Fig. 2) to the upper arm 108 of a lever which is pivoted at 109 and provided with a cam arm 110 operated by a cam 111 keyed to cam shaft 13. Cam lever 108—110 is supported by a bracket arm 112 which projects laterally from an upright 113 which carries the T-shaped guide 104. It will be seen by this description that cam 111 operates the sliding bar 106 every time a safety pin is completed. From an inspection of Fig. 6 it will be seen that the shaft 98 is provided with a collar 114 to prevent its being lifted in its bearings. A key 115 carried by the upper end of the shaft fits a slot in the lower end of the tubular axis 116 of the holder 117. Said holder consists of 50 a cylindrical body connected by radially disposed spokes 118 with the central hub portions 119 which are rigidly connected to the tubular axis 116. As shown in Fig. 6, the lower hub portion 119 is provided with a reduced end 120 upon which is journaled a bottom plate or disk 121, said plate being movably supported by an annular flange 122 which is rigidly secured to the reduced end 120. As shown in Figs. 6 and 7 the cylindrical portion of the holder is provided with a plurality of shield-containing channels or chambers 123 which extend throughout the length of said cylindrical portion. Said chambers are adapted to receive and hold a supply of safety pin shields in the prede-

termined order in which they are introduced thereinto. Opening through the plate or disk 121, is an aperture which conforms to the cross-section of each of these passageways or chambers. It will be seen therefore, that whenever such opening of the disk 121 is in register with the upper end of the chute section 92 and a chamber 123 above it, the supply of shields contained in such chamber will discharge into the upper section of the chute and thence downwardly until the lowermost shield is intercepted by the spur 74 carried by the spring 72. In order to lock the holder in such a position, a latch 124 is mounted on the base plate 93. In order to adapt the holder to be removed from the base plate 93 to be re-filled, a latch 125 carried by the holder is adapted to releasably engage the rotary plate 121 to hold the only aperture therein out of register with any of the chambers 123. A detail of one of these latches will serve for both and is shown in Fig. 10. Thus a stud 126 secures the flange 127 to base plate 121. A spring housing 128 which is carried by the flange 127, contains a spring 129 which is interposed between a collar 130 and the outer wall 131 of the housing. As shown in Fig. 1, a two piece slide bar 132 is movably connected at 133 to a connecting rod 134. Said bar 132 is reciprocably mounted in the shank portion of the T-shaped slide 104 and is of sufficient size to fill the gap between the rods 103 and 106, so that when it has been moved toward the right, a reciprocatory movement of the rod 106 will effect a movement of the ratchet 99 a distance of one tooth which is sufficient to move an empty chamber of the holder away from the upper end of the chute, and to bring a filled chamber into register therewith, which immediately discharges into said chute. The upper end 135 of an irregularly bent rod is connected to the rod 134. The lower end 136 thereof (see Fig. 5) is connected by an angularly bent portion 137 with the upper section 135, said portion 137 being journaled on a pin 138 carried by a bracket 139. A spring 140 serves to normally press the lowermost portion 136 of said rod against a shield 141, if there is one present. In the event of there being no shield at this point in the chute, spring 140 effects a displacement of the slide 132, so that it is interposed between rods 103 and 106. In consequence, the next movement of the cam bar 110 causes a movement of the holder as hereinbefore mentioned.

I claim:

1. In a machine of the character described, an article holder, a chute suitably disposed to receive articles from said article holder, means for detecting the presence of an article in said chute, and means controlled by said detecting means for mov-

ing said holder into position to discharge into said chute.

2. In a machine of the character described, the combination with a feed chute, of an article-holder provided with a plurality of chambers or passages adapted to be successively brought into communication with said chute, means for moving said article holder and means depending on the presence 10 of an article in said chute for controlling the movement of said article-holder moving means.

3. In a machine of the character described, a feed chute, a detector finger suitably 15 mounted and arranged to be engaged by an article in said chute, an article-holder provided with a plurality of chambers or passages, said article-holder being suitably mounted to move said chambers or passages 20 successively into position to communicate with said chute, and means under the control of said detector finger for imparting a step by step movement to said article holder.

4. In a machine of the character described, a feed chute, a rotary barrel provided with a plurality of article holding chambers, said barrel being mounted to turn on an axis suitably disposed to bring said chambers successively into position to discharge into said 30 chute, power driven means for imparting a step by step movement to said barrel, said means including a detector for determining the presence or absence of articles in said chute, and an instrumentality operated by 35 said detector to render said step by step means operative or inoperative.

5. In a machine of the character described, the combination with a feed chute, of means for feeding articles from said chute, means 40 adapted to deliver successive supplies of articles to said chute, and means for periodically operating said article-delivering means including a finger normally held by an article in said chute in position to render 45 said periodic operating means inoperative and adapted to render said periodic operat-

ing means operative when said finger is released.

6. In a machine of the character described, the combination with a feed chute, of means 50 for feeding articles from said chute, means adapted to deliver successive supplies of articles to said chute, and means for periodically operating said article-delivering means including a finger normally held by 55 an article in said chute to render said operating means inoperative and adapted to render said operating means operative when said finger is released, said operating means including a movable element connected to 60 and moved by said finger into successive positions to render said operating means operative or inoperative.

7. In a machine of the character described, the combination of a chute for articles to be 65 fed, a support arranged adjacent the upper end of said chute, a holder provided with a plurality of chambers for articles to be fed, said holder being journaled on said support and arranged to bring said chambers or 70 passages successively into register with the upper end of said chute, a ratchet carried by said holder, a pawl for operating said ratchet, means for driving said pawl, and means actuated by articles in said chute for 75 controlling said driving means.

8. In a machine of the character described, the combination with a chute, of means for detecting the presence of an article in said chute, a support arranged adjacent the upper 80 end of said chute, a shaft journaled in said support, a ratchet mounted on said shaft, a pawl for operating said ratchet, a reciprocable power driven bar normally disconnected from said pawl, means controlled by 85 said detecting means for transmitting power from said reciprocable bar to said pawl, and a holder for articles provided with chambers or passages adapted by said ratchet to be moved successively into register with the 90 upper end of said chute.

WILLIAM A. COURTLAND.
